UNITED STATES PATENT OFFICE.

MARIE E. KAUFMANN, OF PLATTSMOUTH, NEBRASKA.

DESIGN FOR A NURSE'S PIN.

43,107.

Specification for Design.

Patented Oct. 8, 1912.

Application filed July 19, 1912. Serial No. 710,489. Term of patent 7 years.

To all whom it may concern:

Be it known that I, MARIE E. KAUFMANN, a citizen of the United States, residing at Plattsmouth, in the county of Cass and State of Nebraska, have invented a new, original, and ornamental Design for a Nurse's Pin, of which the following is a specification, reference being had to the accompanying drawing, forming part thereof.

The figure is a plan view showing my new design.

I claim:

The ornamental design for a nurse's pin, as shown:

In testimony whereof, I affix my signature, in presence of two witnesses.

MARIE E. KAUFMANN.

Witnesses:

J. M. ROBERTS,
O. G. RICHY.
